BILLFOLD, POCKET SECRETARY,
AND THE LIKE

Paul L. Ogden, New York, N. Y.

Application April 19, 1944, Serial No. 531,732

1 Claim. (Cl. 150—38)

This invention relates to billfolds, pocket secretaries and the like, and provides improvements therein.

The invention is a billfold, pocket secretary, and the like, having a plurality of pockets for paper money (bills), letters, documents, memoranda, and the like, providing exceptional accessibility to the contents and security against accidental loss of the contents when opening the same and inserting and extracting contents.

An embodiment of the invention is illustrated in the accompanying drawing, wherein

Fig. 1 is a plan view of the article viewed from the inside;

Fig. 2 is a perspective view looking from above at an angle of about 45° and showing the exceptional accessibility to the pockets provided by the construction;

Fig. 3 is a cross-section on the line 3—3, Fig. 1.

The invention may receive other embodiments than that specifically illustrated and described.

Referring to said drawing, numeral 10 designates the outer side or cover, and numerals 11, 12 and 13, a plurality of leaves, which, together with the cover 10, constitute a plurality of pockets 15, 16, 17, for bills, letters, etc. A greater or less number of leaves may be used. The cover and leaves may be made of any suitable material, as leather, leather substitutes, silk, or cotton fabric, etc., and the cover, on the inside, and the leaves may be lined in a way similar to many styles of billfolds and pocket-books now made.

The leaves 11, 12, 13, are fastened to the cover 10 along a short edge or side 20 and a long edge or side 21, by stitches of thread, as shown, or in any other suitable manner.

The leaves 11, 12, 13, may be of successively smaller area than that of cover 10, substantially as illustrated, and the free edges at the sides 22 and 23 are successively spaced inward from the corresponding edges of cover 10, which arrangement facilitates access to the individual pockets.

Secured to the cover 10 at side 23 is a tongue or strap 25, the tongue being attached by stitches of thread 26, or by other suitable means. The tongue 25 extends over the free edges of the leaves 11, 12, 13, at side 23. The tongue is attached to the leaf 13 by a suitable keeper 27 in such manner that the tongue is capable of a limited amount of lengthwise movement with relation to the leaf. The keeper 27 may be, as shown, a loop extending across the tongue and attached to the leaf 13, and between which and the leaf the tongue 25 can slide. In the form shown, the tongue is provided with ears or enlargements 30 which act

to prevent the tongue being pulled out from the keeper or loop 27. The part of the tongue on which the ears 30 are provided extends inwardly somewhat beyond strap 27 when the leaves and the contents of the pockets lie close together. When one or more of the leaves 11, 12, 13, is spread from the cover 10, or from the other leaves, the tongue slides in the loop 27 until stopped by the enlargements 30 on the tongue, as illustrated in Fig. 2. The tongue enables the leaves to be widely separated at the top and free side, one from another, or from the cover 10, and also confines the contents of the pockets at the free side of the leaves, and prevents them from falling out when the contents are being examined or some of the contents being removed. As contents, at times, are unnoticed when they fall out, loss is prevented, and this is of much importance with an article such as a billfold.

20 Supplementary pockets 33, 34, for cards or the like, may be provided on the inside leaf 13 in a variety of types.

To extract (or insert) a bill, letter, or the like, from the billfold, the leaf at the front of the 25 pocket containing the bill to be removed (leaf 11, Fig. 2, for example) is pulled away from the leaf or cover behind it, and the pocket between the leaf and the cover, or between two leaves, opens widely throughout the greater part of the length 30 of the pocket, as illustrated in Fig. 2. This wide separation is effected by reason of the freedom of the leaves at the longitudinal side 22 and the right-hand side 23, and the slidability of the tongue 25 in loop 27, which slidability is limited 35 by the enlargements 30 on the tongue. The tongue 25 extending across the open ends of the opened pockets, as well as across the ends of the unopened pockets, prevents normal contents from falling out and being lost. The wide opening of 40 the pockets afforded by the construction enables the contents of an open pocket to be readily examined and a desired bill or the like to be readily removed or inserted. The security afforded by the tongue 25 and its keeper is obtained with a 45 minimum of increase of bulk of the billfold.

What is claimed is:

A billfold type article comprising a cover and a plurality of leaves, means fastening said cover and leaves together along two adjacent edges leaving the other adjacent edges of the cover and leaves free, the cover and leaves providing a plurality of pockets for bills and the like each pocket having two of its sides open, a tongue attached to the cover at one of said free edges and cooperating with a keeper attached to the correspond-

ing free edge of the inner leaf and extending across one of the open sides of the pockets at one of the free edges of the leaves and acting to prevent loss of contents from the pockets at said one of the open sides thereof; said tongue having limited longitudinal movement in said keeper and means for preventing separation of the tongue from the keeper, the construction and arrangement being such that a leaf may be widely sep-

arated from the cover, or from another leaf, and a pocket opened widely for ready accessibility in examining, removing and inserting contents, and also such that security against loss of contents of an opened pocket is provided by the said tongue at the side of the pocket across which said tongue extends.
